(57) **CLAIM**

The ornamental design for a TV receiver with graphical user interface, as shown and described.

DESCRIPTION

FIG. 1 is a front view of the first image in a sequence for a TV receiver with graphical user interface showing our new design;

FIG. 2 is a front view of the second image thereof after changing;

FIG. 3 is a front view of the third image thereof after changing; and,

FIG. 4 is a front view of the fourth image thereof after changing.

The broken lines illustrate portion of the article and form no part of the claimed design. The appearance of the transitional image sequentially transitions between the images shown in FIGS. 1-4. The process or period in which one image transitions to another image forms no part of the claimed design.
